UNITED STATES PATENT OFFICE

2,430,208

SEWING MACHINE SUPPORT

Clarence S. Best, Belvidere, Ill., assignor to
 National Sewing Machine Company, Belvidere,
 Ill., a corporation of Illinois

Application June 18, 1945, Serial No. 600,132

5 Claims. (Cl. 248—22)

1

This invention relates to sewing machine supports, either stationary or portable, and particularly to a table, cabinet or other support provided with means for resiliently carrying the bed plate and sewing head of a sewing machine.

One of the objects of the invention is to support the sewing mechanism in an efficient manner and to eliminate sidewise vibration and vertical movement of the mechanism relatively to its support.

Another object is to support the sewing mechanism without the aid of clamping or fastening means, thereby permitting the machine to be placed on its support and to be removed therefrom with the utmost ease.

In the drawings:

Fig. 1 is an elevational view of a conventional sewing machine head and bed plate, mounted on a support embodying my invention, the support being shown in section and partly broken away.

Fig. 2 is a fragmentary, longitudinal vertical sectional view, on an enlarged scale, through the support and bed plate, taken in the plane of the line 2—2 of Fig. 3.

Fig. 3 is a fragmentary, transverse vertical sectional view, on an enlarged scale, through the support and bed plate, taken in the plane of the line 3—3 of Fig. 2.

Fig. 4 is a perspective view of the spring metal plate which constitutes part of the special mounting means in the support, detached from the other parts.

In that embodiment of the invention shown in the drawings, a conventional sewing machine comprises the bed plate 10, upright standard 11, overhanging arm 12 and sewing head 13.

The support for the machine may be a table, cabinet or the like, and its top 14 is cut away to present the vertical surfaces 15 and 16 and the horizontal surfaces 17, for the purpose of forming a ledge and receiving and supporting the bed plate 10 of the machine. The special mounting means of my invention is located in the ledge portion 18 of the support as indicated in Fig. 2.

Said special mounting means comprises the spring metal plate 19 which consists of a curved plate member 20, apertured centrally at 21, having flat arms 22, 22 at each end, the arms 22 of each end being spaced apart as indicated at 23. The mounting means also comprises the solid stud shown herein in the form of a cylindrical member 24 preferably made of leather, rubber or other suitable material, together with three screws, 25, 25 and 26. The cylindrical member

2

24 is the weight carrying member. The spring metal plate 19 is secured to one end of the stud 24 by means of the screw 26 passed through the aperture 21 into the cylinder 24, with the convex surface of the member 20 toward the end of the cylinder 24. The stud 24 need not be cylindrical but may be square or other shape in cross section.

To attach the special mounting means to the support 14, the portion 18 thereof is provided with bores or recesses adapted to receive the cylinder 24 of each mounting device, and after the cylinders have been positioned as shown in Figs. 2 and 3, the screws, 25, 25 are inserted 15 through the spaces 23 between the arms 22 of the plate 19 and screwed into the underside of the part 18 of the support 14.

When attached to the support 14, the cylinder 24 of each device will protrude somewhat above 20 the supporting surface 17 of the portion 18 of the support, thus presenting a surface 27 on which rests the bed plate 10 when the machine is in operative position.

The character of the material of which the 25 cylinders 24 are made is such that it provides frictional engagement between the supporting cylinders and the sewing machine and prevents relatively sidewise movement between the parts. Furthermore, the resilient character of the spring 30 metal plate, preferably augmented by that of the cylinder 24, is such that shocks are transmitted vertically to the plate, and sidewise vibration and vertical movement of the sewing mechanism is avoided.

The form of the several parts of my invention, 35 their construction and assembled relationship, are such that the vibration and relative movement of the sewing machine and support found in prior art constructions are eliminated, and the 40 usual shocks resulting from operation of the machine, especially when motor driven, are absorbed by the support without imparting vibrations to the sewing mechanism.

The absence of fastening and clamping means 45 is a great convenience in placing and removing the machine from the support.

Changes may be made in the form and details 50 of construction shown herein, without departing from the scope of my invention as set forth in the appended claims.

I claim:

1. A sewing machine support provided with means for mounting a sewing head thereon and retaining the head against vibration without the aid of clamping or fastening devices, comprising

a supporting ledge provided with a vertical bore therethrough, a weight-carrying member mounted in the vertical bore and projecting above said ledge, the upper surface of said weight-carrying member being adapted to frictionally engage the machine to be supported, a spring metal plate, means connecting the plate to said weight carrying member beneath the ledge, said plate having end members, and means connecting each end to the under side of the ledge at a distance from the connection between the plate and said weight-carrying member.

2. A sewing machine support provided with means for mounting a sewing head thereon and retaining the head against vibration without the aid of clamping or fastening devices, comprising a supporting ledge provided with a vertical bore therethrough, a weight-carrying member mounted in the vertical bore and projecting above said ledge, the upper surface of said weight-carrying member being adapted to frictionally engage the machine to be supported, a spring metal plate having a curved portion, means connecting the curved portion to said weight-carrying member beneath the ledge, said plate having end members and means connecting each end to the under side of the ledge at a distance from the connection between the curved portion and said weight-carrying member.

3. The sewing machine support defined by claim 2, in which the curved portion of the spring metal plate is curved upwardly between the ends of the plate, and the weight-carrying member is connected to the convex surface of said curved portion.

4. A sewing machine support provided with means for mounting a sewing head thereon and retaining the head against vibration without the

aid of clamping or fastening devices, comprising a supporting ledge provided with a plurality of vertical bores therethrough, a weight-carrying member made of resilient material mounted in each vertical bore and projecting above said ledge, the upper surface of each weight-carrying member being adapted to frictionally engage the machine to be supported, spring metal plates having centrally curved portions, means connecting the upper convex surfaces of the curved portions of the plates to said weight-carrying members, said plates having end members comprising spaced apart fingers, and headed screws inserted between said fingers and into the under side of the ledge for connecting said plates to said ledge.

5. A sewing machine support provided with means for mounting a sewing head thereon and retaining the head against vibration without the aid of clamping or fastening devices, comprising a supporting ledge, a yielding plate, means connecting the plate to the supporting ledge, a weight carrying member having an upper surface projecting above the ledge adapted to frictionally engage the machine to be supported, and means connecting the weight carrying member to said plate at a distance from the connection between the plate and said supporting ledge.
